UNITED STATES PATENT OFFICE.

SYLVESTER A. VERNIA, OF INDIANAPOLIS, INDIANA.

GUN.

1,269,661.

Specification of Letters Patent. Patented June 18, 1918.

Application filed January 21, 1918. Serial No. 212,935.

To all whom it may concern:

Be it known that I, SYLVESTER A. VERNIA, a citizen of the United States, and a resident of Indianapolis, county of Marion, and State of Indiana, have invented a certain new and useful Gun; and I do hereby declare that the following is a full, clear, and exact description thereof, reference being had to the accompanying drawings, in which like numerals refer to like parts.

This invention relates to fire arms and the prime object of the invention is to provide a combination rifle and shot gun and so construct the same as to be practically the same weight and dimensions as the double barreled shot gun.

A further feature of the invention is to provide a pump arrangement for conveying shells from either of the magazines into the firing chamber of either of the barrels. A further feature of the invention is the provision of means for quickly separating the barrels from or attaching the same to the receiver of the fire arm.

A further feature of the invention is the provision of a slide handle which may be swung laterally to engage the shell removing mechanism of either of the magazines. A further feature of the invention is the provision of means for locking the slide block in position to engage and operate one or the other of the shell removing mechanisms.

The full nature of the invention will be more fully understood from the accompanying drawings and the following description and claims.

Figure 1 is a top plan view of the fire arm ready for use. Fig. 2 is a side elevation thereof. Fig. 3 is an end elevation of the barrel receiving end of the receiver as seen on line 3-3 of Fig. 2. Fig. 4 is a similar view of the barrel connecting block as seen on line 4-4 of Fig. 2. Fig. 5 is a sectional view as seen on line 5-5 of Fig. 7 showing the slide handle in position to remove shells from the shot gun magazine. Fig. 6 is a similar view showing the slide handle in position to remove cartridges from the rifle magazine. Fig. 7 is an elevation, partly in section, of the barrel portion of the fire arm detached from the receiver. Fig. 8 is a detail sectional view of the magazine for holding the shells. Fig. 9 is a perspective view of the locking sleeve employed for locking the rifle magazine in engagement with the receiver of the fire arm. Fig. 10 is an en-

larged detail sectional view as seen on line 10-10 of Fig. 7.

Referring to the drawings in which similar reference numerals designate corresponding parts throughout the several views, 1 indicates a stock of a fire arm which may be constructed in any preferred manner, the receiver 2 at the outer end of the stock being designed to receive rifle cartridges at one side and shot gun shells at the opposite side. The mechanism for receiving and placing the cartridges and shells in their respective barrels are of the usual or any preferred construction.

Extending forwardly from the stock 1 is a shot gun barrel 3 and a rifle barrel 4, said barrels extending through a barrel connecting block 5. The barrels 3 and 4 extend a distance through the barrel connecting block 5, the barrel 3 having segmental threads 6 thereon which enter a socket 7 in the forward end of the receiver 2, said socket also having segmental threads 8 which coöperate and interlock with the segmental threads 6 on the barrel 3, the threads 6 and 8 being so arranged that by turning the barrel 3 and barrel connecting block 5 at right angles to their normal position, the threaded end of the barrel 3 may be readily entered into the socket 7 and by then rotating the barrel and barrel connecting block and bringing them into proper registration with the receiver 2, the threads 6 and 8 will be properly interlocked with each other.

As the rifle barrel 4 also projects a distance through the barrel connecting block 5, the end of the receiver 2 is provided with a slot 9, the upper edge of which is open so that the barrel 4 will readily move downwardly into the slot when the barrel and barrel connecting block are rotated to interlock the threads 6 and 8, a ledge 10 being provided on the barrel connecting block for covering the entrance of the slot when the barrel 4 has been brought into proper registration with the receiver.

In order to securely lock the barrels and barrel connecting block in engagement with the receiver, a sleeve 11 is introduced around the magazine 12 for the rifle barrel, said sleeve projecting through the barrel connecting block and having segmental threads 13 thereon for engagement with segmental threads 14 formed in the socket 15 in the end of the receiver 2, so that when the barrel connecting block and barrels have

been rotated to the proper position the sleeve 13 is turned until the threads thereon are in position to pass between the threads 14 of the socket 15, when the sleeve is moved 5 lengthwise and the threads 13 brought into position to interlock with the threads 14, then the sleeve 11 is given a quarter turn through the medium of the handle 16 on the sleeve. This, in conjunction with the interlocking of the barrel 3, securely locks the barrel connecting block and barrels against independent movement of the receiver and holds the barrels and magazines in proper operative position. In addition to locking 10 the barrels and barrel connecting block in position by the interlocking threads, a screw 17 may be threaded through the wall of the receiver 2 so as to engage one edge of the ledge 10, the screw 17 binding against the ledge to such an extent as to normally hold the barrel connecting block against swinging movement.

The slides 18 and 19 for the magazines 20 and 12 respectively are spaced a slight distance apart and between them extend arms 21 carried by the slide handle 22, said slides having notches 23 therein for engagement with heads 24 on the arms 21, said arms being so arranged that when in engagement 25 with the notches of one of the slides they will be out of engagement and out of contact with the other slide, whereby but one slide will be operated at a time. The slide handle 22 is slidably mounted upon a rod 25 and is spaced a sufficient distance from the magazines that it may be swung laterally to disengage the arms from notches on either of the slides, and any suitable means may be employed for temporarily holding 30 the arms in engagement with either of the slides, such as the provision of a collar 26 on one of the arms 21, which collar surrounds the rod 25 and through said collar is formed a bore 27 in which is placed a ball 45 27^a, said ball being adapted to engage one or the other of the grooves 27^b or 27^c, which grooves extend longitudinally of the rod 25. In order to hold the ball in yielding engagement with the grooves 27^b or 27^c, a spring 50 27^d is placed above the ball 27^a, the upper end of the spring resting against a cap 27^e, threaded in the upper end of the bore 27. By this construction it will be seen that when the slide handle and arms are turned 55 to the position shown in Fig. 5 the ball 27^a will be in engagement with the grooves 27^b as shown in Fig. 10 and when the slide handle is thrown to the position shown in Fig. 6 the ball will engage the grooves 27^c and 60 when the ball is in engagement with either of the grooves the slide handle will be held in its respective adjusted position until such time as lateral pressure is applied thereto to swing the same in the opposite direction.

65 The shells 28 are ejected from the maga-

zines by means of springs 29, said springs having heads 30 attached to one end thereof which force the shells out of the magazines, while the opposite ends of the springs are attached to sleeves 31 at the outer ends of 70 the magazines, these sleeves having latches 32 which enter openings 33 in the magazines for locking the sleeves and springs in position in the magazines, springs 34 being employed for normally holding the latches 75 seated in the openings.

In order to lend a symmetrical appearance to the two barrels without materially increasing the weight of the rifle barrel, a jacket 35 of aluminum or similar light material of the same dimensions of the shot gun barrel may be introduced over the rifle barrel.

In attaching the barrels to the receiver, supposing the receiver to be in the right hand, and the barrels in the left, the barrels are rotated until the rifle barrel is positioned directly above the shot gun barrel, when the threaded end of the shot gun barrel is introduced into the socket 7 and the barrels then reversely rotated until the rifle barrel is properly seated in the slot 9, this operation interlocking the segmental threads 6 and 8 and bringing the ledge 10 into position to close the upper end of the slot 9. 95

The sleeve 11 is then given a quarter turn from its natural position and then moved longitudinally through the barrel connecting block 5 and into the socket 15, when said sleeve, through the medium of the handle 16, is rotated a quarter of a turn thereby interlocking the threads 13 and 14. The screw 17 is then turned inwardly until the inner end thereof firmly binds against the edge of the ledge 10, thereby positively locking 105 the parts of the fire arm together.

If the shot gun is then to be used, the slide handle 22 is swung to the position shown in Fig. 5 and if desired may be held in this position by the ball 27^a entering the 110 groove 27^b, thus securely locking the arms 21 in engagement with the notches 23 on the slide 18 and when the slide handle is moved longitudinally of the barrel a shell will be placed in position and entered in the firing 115 chamber of the shot gun barrel. On the other hand if it is desired to use the rifle, the slide handle 22 is swung into the position shown in Fig. 6 thereby engaging the arms with the slide 19 and disengaging 120 them with the slide 18, and when the slide handle is operated the rifle cartridges will be fed into the firing chamber of the rifle.

In taking down the barrels the handle 16 of the sleeve 11 is swung downwardly and the screw 17 released from the ledge 10, when the barrels and barrel connecting block may be rotated to release the barrel 3 from the end of the receiver, the sleeve 11 having previously been moved outwardly 130

along the magazine 12 for disengaging the end thereof from the socket 15.

From this construction it will be seen that I have provided a combination fire arm and one that can be quickly taken down or attached together and when attached together the parts will be held against relative movement independently of each other. By arranging the barrels so that they can be readily separated from the receiver of the fire arm the parts can be more compactly stored for transportation and likewise by removing the barrels from the receiver, said barrels can be more thoroughly and more quickly cleaned. It will likewise be seen that by arranging the slide handle in the manner shown, but a single handle will be required to operate either of the magazines for introducing shells into the receiving chambers and by providing a temporary locking mechanism for holding the slide handle in its adjusted position but one of the magazines will be operated at a time and without danger of accidentally operating the other magazine.

It will further be seen that by providing both a shot gun barrel and a rifle barrel the fire arm is adapted for both large and small game, without requiring two separate fire arms and this result can be accomplished without materially increasing the weight of the fire arm.

The invention claimed is:—

1. In a fire arm, the combination with a receiver, having a pair of sockets therein of a pair of barrels connected together, one of which is threaded and adapted to engage one of the sockets of the receiver, shell containing magazines co-operating with said barrels, and a threaded sleeve on one of said magazines adapted to engage the other socket of said receiver, whereby the barrels will be locked into engagement with the receiver.

2. In a fire arm, the combination with a stock having a receiver thereon, said receiver having a pair of sockets and a slot formed therein, said sockets having segmental threads, of a pair of barrels for co-operation with said receiver, one of said barrels being threaded and adapted to engage

the threads of one of the sockets, and the other barrel to enter said slot, magazines co-operating with said barrels, and means on one of the magazines for engaging the other 55 socket of the receiver whereby the barrels will be locked into engagement with the receiver.

3. In a fire arm, the combination with a stock and a receiver thereon, said receiver 60 having a pair of sockets and a slot therein, of a barrel connecting block, a pair of barrels having one of their ends projecting through the barrel connecting block, one of said barrels being adapted to interlock with 65 one of the sockets of the receiver and the other barrel to enter said slot, and means to lock said barrels and barrel connecting block against independent movement with respect to the receiver. 70

4. In a fire arm, the combination with a stock, and a receiver thereon, of a pair of barrels, a shell receiving magazine for each barrel, and a pivotally mounted, laterally movable single slide handle for operating 75 one or the other of said magazines to release the shells therefrom.

5. In a fire arm, the combination with a stock, and a receiver thereon, of a combined shot gun barrel and a rifle barrel, means to 80 removably attach the barrels to said receiver, a shell receiving magazine for each barrel, a shell releasing slide for each magazine, a pivotally mounted, laterally movable single slide handle for operating either of said 85 slides, and means to hold the slide operating mechanism in engagement with either of the slides.

6. In a combined shot gun and rifle, the combination with a shot gun barrel and a 90 rifle barrel, and a magazine for each barrel, of a shell releasing slide for each magazine, a single pivotally mounted, laterally swing- 95 ing slide handle, arms on said handle for engagement with one or the other of said slides when the handle is swung laterally, and means to lock the slide handle in engagement with one or the other of the slides.

In witness whereof I have hereunto affixed my signature.

SYLVESTER A. VERNIA.
